UNITED STATES PATENT OFFICE.

HERBERT W. CHENEY, OF MILWAUKEE, WISCONSIN, ASSIGNOR TO ALLIS-CHALMERS MANUFACTURING COMPANY, OF MILWAUKEE, WISCONSIN, A CORPORATION OF DELAWARE.

ELECTROMAGNETIC SWITCH MECHANISM.

Application filed February 9, 1921. Serial No. 443,499.

To all whom it may concern:

Be it known that HERBERT W. CHENEY, a citizen of the United States, residing at Milwaukee, in the county of Milwaukee and

5 State of Wisconsin, has invented a certain new and useful Improvement in Electromagnetic Switch Mechanism, of which the following is a specification.

This invention relates to electromagnetic 10 switch mechanisms and may be applied in motor starters and particularly to that type which is automatic in operation.

One of the objects of the invention is the provision of a self-contained switching device which is separately salable, and which may be applied to controllers of the type in which a motor is first connected to a potential reducing device and then directly to the line. The self-contained switching device 20 may, however, be also applied to electromagnetically operated controllers or switches in general and is particularly applicable to such as are of the double throw type. When so applied, it is an object of the invention 25 that such switches or controllers will become automatic in character and function to first move to one predetermined position and a predetermined time thereafter to another position.

30 Another object of the invention is the provision of a simple and efficient self-contained switching device, which may be easily applied in the types of switches or controllers as noted above. A more specific object 35 is the provision of a self-contained unit, which may be operatively associated with switches and controllers by means of a single mechanical connection. Other objects will appear hereinafter as the description of 40 the invention proceeds.

The novel feature of the invention will appear from this specification and the accompanying drawings forming a part thereof, and disclosing one embodiment thereof, 45 and all these novel features are intended to be pointed out in the claims.

In the drawings, Fig. 1 is a front elevation of a unitary or self-contained switching device embodying the invention, as it 50 may be applied in connection with an electromagnetically operated motor controller.

Fig. 2 is a side elevation of a unitary switching device, such as shown in Fig. 1, but on a larger scale.

Fig. 3 is a vertical sectional view of such 55 a device as shown in Fig. 2.

Fig. 4 is a front elevation of the device, shown in Fig. 2.

Figs. 5 and 6 are fragmentary views in front elevation of some of the parts shown 60 in Fig. 4, but in different operative positions.

Figs. 7 and 8 are diagrams of the manner in which the switching device, such as disclosed in Fig. 4, may be electrically connected 65 and associated with electromagnetically operated controllers of different types.

The control unit, or automatic switching device 1, is shown in Fig. 1 in operative relation 70 to the electromagnetic actuating mechanism 2 of a motor controller. The controller is provided with an operating mechanism 3 and movable and stationary contacts 4. Inasmuch as the specific form 75 of the electromagnetic actuating mechanism, operating mechanism, and movable and stationary contacts is not material as far as the invention herein claimed is concerned they need not be further described; they are, 80 however, diagrammatically shown in Fig. 7, and their operation and relation to the control unit 1 will be more fully set forth hereinafter.

Referring now more particularly to Figs. 85 2, 3 and 4: the control unit is provided with a longitudinally movable member 5 here shown as of tubular form, which is movable in guides 6, 7 suitably mounted in the legs 8, 9 respectively of the U shape frame 10. 90 The frame 10 is fastened in any suitable manner to a board or support 107. The tube 5 is provided at its lower end with an apertured plug 11. A rod 12 disposed within the tube passes through the aperture in the 95 plug, and is provided at its upper end with a member 13, by which it is pivotally connected to a lever 14, one end of which lever is pivoted to a lug 15, rigidly associated with the board 107. The other end of the 100 lever 14 is connected by means of a link 16 to the piston of a dash pot 17. A spring 106 is disposed around the rod 12 and between the member 13 and plug 11. The lever 14 is here shown as passing through 105 slots 18 in the tube 5.

The upper end of the tube 5 is provided with an apertured plug 19. A rod 20 asso-

ciated with an armature or core 21 of a magnet 22, passes through the aperture in the plug 19. The lower end of the rod 20 has a collar 81 fastened thereto. A spring 82 is disposed around the rod 20 and between the shoulder formed by the lower end of the core 21, and the plug 19.

A floating lever 23 is pivoted on the pin 24 carried by the armature 21. Operatively associated with the lever 23, are contacts 25, 26. The contact 25 is here shown as U shaped and is mounted on a lever 27 pivoted on the pin 28. The pivot pin 28 is mounted on an insulating board 29 carried by the main board 107, and is provided with terminal 92, at the rear of the board 29. The lever 23 carries a roller 30, which is disposed between the lateral portions of the U shaped contact 25, whereby movement in either an upward or downward direction of said roller, causes the lever 27 to swing about the pivot 28. The contact 25 is adapted to engage a stationary contact 31 mounted on the board 29 and provided at its rear end with a terminal 38. Contact 31 serves at the same time as a stop for contact 25. In its open circuit position, the contact 25 engages the stop 32, mounted on the board 29. The contact 26, which is of the same form as contact 25, is provided with a button-like contact surface 33, best seen in Fig. 3. The contact 33 is adapted to engage and slide over the stationary contact studs 34, 35, which are provided respectively with transversely extending stops 36, 37. The contact studs 34, 35 pass through the board 29, and are provided at the rear with terminals 39, 40. The contact 26 is mounted on a lever 41, swingable about the pivot 42. The pivot 42 is mounted on the board 29, passing therethrough, and provided at the rear with a terminal 96. The lever 23 is provided with a roller 43, disposed between the lateral portions of the U shaped contact 26. When the roller 43 is moved in an upward direction by the lever 23, the contact surface 33 will slide over contact 35, then slide onto contact 34, leaving contact 35, the upward motion being stopped by the transverse member 36. The downward motion of contact 36 is stopped by member 37, as indicated in Fig. 4.

The pivot pin 44, of the roller 43, is extended sufficiently so that a latch 45 may engage therewith. The latch 45 is pivotally mounted on the pin 46, carried by a bracket 47. The bracket 47 may be integral with the bracket 51, here shown as mounted in any suitable manner on the leg 9. The latch 45 is so mounted, or proportioned, as to engage and hold the pin 44 when the contact has reached its lower limiting position, as shown in Fig. 4. A spring 48 is provided for biasing the latch 45 into engaging position with respect to pin 44, and is here shown as connected to an extension 49 on

the latch, and to the lug 50 forming part of the bracket 51. The bracket 51 is provided with another lug 52 and between this and the lug 50 is pivotally mounted a trip member 55 provided with pintles 53, 54, passing through holes in the lugs 50, 52. The trip member 55 is provided with a rearward extension 56, disposed over a lateral extension 57 on the latch 45. The trip member is also provided with a forward extension 58, provided with an adjusting screw 59 held in any desired position by means of a lock nut 60. The screw 59 is so disposed as to be engaged by the lever 14 when the latter is swung in a counter-clockwise direction.

A bifurcated lever 61 has its two portions pivotally related at diametrically opposite points with the guide 7, by means of pivot screws 62, 63 as best seen in Fig. 3. Referring now to Fig. 4: the lever 61 is connected by means of a link 64 to the lever 23. A pivot pin 65 forming a pivotable connection between the link 64 and the lever 23, is located on the same side of the pin 24 as the contact 26. The other end of the lever 61 has pivotally connected thereto, a downwardly extending rod 66. The lower end of the rod 66 passes freely through a hole in the extension 67 on a clamp 68. The lower end of the rod 66 is threaded and provided with a pair of lock nuts 69, 70, whereby the effective point or position of the engagement as between the extension 67 and the rod 66, may be determined. The rod 66 is biased in an upward direction, by means of a spring 71, fastened to a transverse pin 72 on the rod 66 and to the leg 9.

The clamp 68 surrounds the tube 5 and is also provided with a rearward extension 73, having a hole 74, (see Fig. 2). The extension 73 may be connected in any suitable manner with a selected moving portion of the electromagnetic controller with which it is desired to associate the control unit. In the instance disclosed, the extension 73 is connected by means of the link 75 (see Fig. 1) to the crank 76 associated with the shaft 77 to the electromagnetic operating mechanism.

The control unit has been illustrated in Fig. 7, as it may be applied in an electromagnetically actuated control of the same general type as shown in applicant's co-pending application, Serial No. 387,287, filed June 7, 1920. The control unit has been thus shown in order that the functions and operation of the various parts thereof may be better understood, but as hereinbefore noted, it is to be understood, that the control unit is applicable to many other forms of electromagnetically actuated controllers as will be apparent to those skilled in the art, one other mode of application being shown in Fig. 8.

Referring now more particularly to Fig. 130

7, the electromagnetic actuating mechanism is here shown as comprising an armature 78, having the legs 79, 80 operatively located with respect to the starting control coil or magnet 83 and a running control coil or magnet 84. One terminal each, of the latter coils, is connected to the conductor 86 at the point of connection 85. The conductor 86 is connected to one terminal of the 5 normally closed switch 87; the other terminal of said switch is connected to conductor 88. Terminal 89 of magnet 22 is connectible to conductor 88. Contact 35 of the control unit is connectible to conductor 90, the other 10 end of which is connected to starting control coil 83. Contact 34 of the control unit is connectible to conductor 91, which is connected to running control coil 84. Terminal 92 of the control unit is connectible to conductor 93, connected to one line 94 of the 15 polyphase supply. A normally open switch 95 has one of its terminals connected to conductor 93 and the other to conductor 88. Terminal 96 of the control unit is connectible to conductor 97 which is connected to line 98 of the polyphase supply. Terminal 89 of the control unit is also connectible to conductor 99 connected to one terminal of the 20 impedance 100 here shown as connected to the contacts 101 of any desired number of abnormal condition relays. The motor controller proper is provided with movable contacts 102 and stationary starting contacts 103 and stationary running contacts 104. The 25 movable contacts and their operative relation to the armature 78 are indicated diagrammatically in side elevation by the contact actuating mechanism 3 associated with shaft 77, and the movable contact "m". The 30 starting and running contacts are indicated by the reference characters *s*, *r*, respectively. Inasmuch as it is immaterial as far as the invention herein claimed is concerned in what specific manner the motor is controlled, 35 it is sufficient to say that the motor 105 is so connected that when the movable contacts are thrown to the right in the figure, a reduced potential will be applied to the motor and when they are thrown to the left, the 40 motor will be connected directly to the line. It will be seen that but a single mechanical connection is necessary between the control unit and the controller to be automatically controlled. All of the parts of the 45 control unit may therefore be mounted on a single board, as has already been clearly set forth, and this board may be mounted on any suitable and desired part of the switch to be controlled, as for example, the 50 rail 108 (Fig. 1). All that is then necessary is to make the appropriate electrical connections, and one way in which this may be done has been illustrated in Fig. 7. A motor controller, for example, may therefore 55 be manufactured and sold with merely an ordinary non-automatic electromagnetic actuating mechanism, and rendered automatic at any time by the bodily addition of a control unit. Different sizes and types of controllers may, moreover, be manufactured 60 and the same form of control unit may be associated with any one of them.

The operation of the control unit, when connected as shown in Fig. 7, is as follows: if the switch 95 is closed, current will flow 65 through conductor 93, switch 95, switch 87, conductor 86, starting coil 83, conductor 90, contacts 35, 33, terminal 96, conductor 97 to line wire 98, thus energizing coil 83 and attracting leg 80 of the armature. This will 70 throw the movable contacts *m* into engagement with contacts *s* and will rotate the crank 76 in a counter-clockwise direction, as viewed in Fig. 7, whereby the tube 5 will be lifted to a predetermined extent. Upward 75 movement of the tube causes the spring 82 to engage the armature 21, thus causing the lever 23 to swing about the pin 44 as a fulcrum and causing engagement of contact 25 with stationary contact 31. The parts 80 will then be in the position shown in Fig. 5. The engagement of contacts 25, 31 bypasses or shunts the switch 95, so that as soon as the operator lets go of the actuating member of switch 95, thereby permitting the switch 85 to open, the circuit previously traced through the starting control coil 83 will be by way of conductor 93, contacts 25, 31, magnet 22 and conductor 88, instead of by way of switch 95. The energization of magnet 90 100 105 110 115 120 125 130 135 22 causes the armature 21, whereby the lever 23 and hence contact 25, is held in position shown in Fig. 5.

The upward movement of the tube 5 also compresses the spring 106 inasmuch as the motion of the lever 14 is retarded by means of the dash pot 17. As the spring 106 expands, it swings the lever 14 in a clockwise direction as viewed in Fig. 7, the speed of the motion being predetermined by the setting of the dash pot. When the lever 14 comes to an engagement with the screw 59 (see Fig. 3) on trip member 58, the latter is swung so as to cause the extension 56 on the trip member to disengage latch 45 from pin 44. The lever 23, being biased upwardly by the pull of magnet 22 on armature 21, will swing about stationary contact 31 as a fulcrum, causing contact 33 to leave contact 35 and engage contact 34. This transfers energization from starting coil 83 to running coil 84 by way of line conductor 98, conductor 97, terminal 96, contacts 33, 34, coil 84, conductor 86, switch 87, conductor 88, magnet 22, contacts 31, 25, terminal 92, and through conductor 93 to line conductor 94. The resulting energization of coil 84 attracts leg 79 of the armature, throwing the movable contacts *m* into engagement with contacts *r*, and by the clockwise rotation of

crank 76, moves the tube 5 downward. The plug 19 and the collar 81 soon come into engagement and the downward movement of the collar pulls the armature 21 away from magnet 22, thereby breaking contact between contacts 25, 31. The lever may be considered, during this action, as turning about pivot 65 as a fulcrum. This movement deenergizes magnet 22, and that portion of the circuit previously traced through magnet 22 from terminal 89, being interrupted, is replaced by conductor 99, impedance 100, through abnormal relay contacts 101 to one of the other line conductors, as has been fully set forth in applicant's copending case hereinabove referred to.

At about the same time that plug 19 engages collar 81, the extension 67 engages lock nut 69, thereby pulling rod 66 downward and pushing the right hand end of lever 23 upward by means of link 64. The downward motion of pivot 24 and upward motion of pivot 65 causes the lever 23 to rotate in a counter-clockwise direction to assume the position shown in Fig. 6. The contact 33 is therefore held in an engagement with contact 34 in spite of the deenergization of magnet 22 and the fact that the tube 5 has been moved in a downward direction. The coil 84 will thus remain energized until its circuit is broken by opening of the normally closed switch 87, or in some other manner as by low voltage, or by the abnormal relay contacts 101, in the instance disclosed.

Another mode of applying the control unit is illustrated in Fig. 8. The electromagnetically actuated controller here shown is of the type in which a motor is first directly connected to a supply line and then to the supply line through fuses. The controller includes a single movable switch member 109 carrying contacts 110, 111, 112. The latter contacts are connectible to the line conductors 113, 114, 115 of a polyphase supply in any desired predetermined order. The controller also includes stationary starting contacts 116, 117, 118 connectible to the terminals of a motor 145, and stationary running contacts 119, 120, 121 connectible to the terminals of the motor 145 through fuses, or other circuit breaking elements 122, 123, 124. The movable switch member 109 is carried by a reciprocable rod 125, here shown as movable in guides 126, 127. The rod 125 and the switch member 109 carried thereby are held in an off or open circuit position by means of springs 128, 129. The rod 125 carries cores or armatures 130, 131 cooperable respectively with a starting control coil 132 and a running control coil 133. One terminal each of the coils 132, 133 is connected to a conductor 134, the other end of which is shown as connected to one terminal of a normally closed

switch 135. The other terminal of the switch 135 is connected to one terminal of a normally open switch 136, the other terminal of which is connected by conductor 137 to line 113. The contact 34 of the control unit is connectible by means of conductor 138 to the remaining terminal of coil 133. The contact 35 of the control unit is connectible by conductor 139 to the remaining terminal of coil 132. The terminal 96 is connectible by conductor 140 to line 115; terminal 89 is connectible by conductor 141 to a point of connection 142 between the switches 135, 136; and the terminal 92 is connectible by conductor 143 to line 113.

Motion may be transmitted to the tubular member 5 through the clamp 68 and extension 73 by any suitable means as by an extension 144 clamped on the rod 125, through the link 75. It is clear, however, that this connection may be of any suitable or desired form, as long as the appropriate motion is transmitted from some movable portion of the switch mechanism to the control unit.

The operation of the control unit when connected as shown in Fig. 8 is as follows: If the switch 136 is closed, current is supplied to the starting control coil 132 by way of conductor 137, switch 136, switch 135, conductor 134, coil 132, conductor 139, contacts 35, 33, terminal 96 and through conductor 140 to line 115. Energization of coil 132 attracts the core 130, thereby moving switch 109 to bring contacts 110, 111, 112 into engagement with contacts 116, 117, 118. It is assumed that the motor 145 is of such type that it is possible to throw it directly across the line in this manner. Upward motion (as viewed in Fig. 8) of the switch 109 causes similar motion of the tube 5 thereby causing closure of contacts 25, 31 as hereinbefore explained in connection with Fig. 7. Closure of the latter contacts by-passes switch 136 by means of the following circuit: conductor 143, contacts 25, 31, coil 22, conductor 141 to point of connection 142. Coil 132, therefore remains energized even though switch 136 is released, and energization of coil 22 holds contacts 25, 31 in engagement. Meanwhile spring 106 has expanded to a sufficient extent so that lever 14 has caused actuation of latch 45, whereby contact 33 leaves contact 35 and comes into engagement with contact 34, thus transferring energization from coil 132 to coil 133, the following circuit being established: contact 140, terminal 96, contacts 33, 34, conductor 138, coil 133, conductor 134, switch 135, conductor 141, coil 22, contacts 31, 25, terminal 92 through conductor 143 to line 113. It will be observed upon comparing Fig. 8 with Fig. 7 that the impedance coil 100, conductor 99 and relay contacts 101 are omitted in Fig. 8, the electromagnetic switch controlled by the control unit being

of simpler form. In view of this, coil 22 must remain energized after the downward motion of tube 5 caused by a similar motion of switch 109 when coil 133 is energized.

- 5 This result is accomplished by a simple adjustment of the lock nuts 69, 70 (see Fig. 4). These nuts are so set that the lower limiting position of the rod 66, as determined by the nut 69 and the limit of motion 10 of the extension 67, is such as to cause an upward motion of link 64 to a position where the pivot pin 65 will no longer act as a fulcrum for the lever 23, as described in connection with Fig. 7. Stated in other 15 words, the collar 81 is not lifted high enough so that there will be effective engagement between the lug 19 and said collar, and therefore the core 21 will not be pulled out of coil 22 nor will the connection 20 between contacts 25, 31 be broken. The foregoing result is possible by reason of the fact that considerable leeway is provided in the position of the button-like contact 25 surface 33 on the contact 34. It is thus possible to so adjust the control unit by means 30 of the lock nuts 69, 70 so that when the tube 5 is moved from its upper to its lower limiting position, contacts 25, 31 will or will not remain in engagement.

From the above described applications, the great flexibility of the control unit will be apparent.

It should be understood that, while two specific uses for the disclosed electromagnetic switch have been illustrated, other uses and relations will readily suggest themselves to those skilled in the art and it is not desired to limit the invention claimed to the exact uses and details of construction 40 herein shown and described.

I claim:

1. In combination with a motor controller of the type having electromagnetically actuated means for connecting a motor in starting relation to a source of supply and for connecting it in running relation to said supply, of self-contained means comprising operatively assembled elements mounted on a common support and detachably associated 45 with said controller for causing said electromagnetically actuated means to automatically connect said motor in starting relation for a predetermined time and then to connect it in running relation.

2. In combination with a motor controller of the type having electromagnetically actuated means for connecting a motor in starting relation to a source of supply and for connecting it in running relation to said supply, of self-contained means comprising operatively assembled elements mounted on a common support and detachably associated 50 with said controller including a single mechanical actuating connection between said self-contained means and said controller, for

causing said electromagnetically actuated means to automatically connect said motor in starting relation for a predetermined time and then to connect it in running relation.

3. A self-contained automatic electromagnetic device comprising operatively assembled elements mounted on a common support and mechanical actuating means connectible by a single mechanical connection to an electromagnetically actuated controller of the double-throw type, terminals for said device connectible to a source of supply and to said electromagnetic actuating means, said device including means for causing said controller to remain in one of its positions for a predetermined time when said electromagnetic actuated means is energized and for then causing it to move to its other position.

4. In an electromagnetic switching mechanism, a longitudinally movable tubular member, a lever having a stationary fulcrum, passing through openings in said tubular member, a dash-pot connected to the end of said lever, a rod carried by said lever and disposed within said tubular member, a compression spring around said rod and disposed between one end of said tubular member and said lever, a magnet, an armature therefor, a rod associated with said armature and having its end disposed within said tubular member, a compression spring between the end of said armature and the end of said tubular member, a floating lever pivotally associated with said armature, contacts operatively associated with the ends of said floating lever, stationary contacts for cooperating with said movable contacts, a latch for holding one end of said floating lever, means whereby said first named lever may trip said latch, and means associated with said tubular member for moving said floating lever in the same direction as effected by said armature.

5. In an electromagnetic switching mechanism, a longitudinally movable member, a dash-pot, a compression spring, means whereby movement of said member in one direction compresses said spring thereby causing actuation of the piston of said dash-pot, a magnet, an armature therefor, means, including a lost motion connection, whereby said longitudinally movable member may move said armature in either direction, movable contacts operatively associated with said armature, stationary contacts adapted to operate with said movable contacts, means for preventing engagement of certain of said contacts, and means responsive to a predetermined movement of said dash-pot piston for rendering said preventing means ineffective.

6. In an electromagnetic switching mechanism, a longitudinally movable member, a dash-pot, a compression spring, means

- whereby movement of said member in one direction compresses said spring thereby causing actuation of the piston of said dash-pot, a magnet, an armature therefor, means, 5 including a lost motion connection, whereby said longitudinally movable member may move said armature in either direction, movable contacts operatively associated with said armature, stationary contacts adapted 10 to cooperate with said movable contacts, means for preventing engagement of certain of said contacts, means responsive to a pre-determined movement of said dash-pot piston for rendering said preventing means ineffective, and means operatively associated 15 with said longitudinally movable member for controlling said certain contacts.
7. In an electromagnetic switching mechanism, a longitudinally movable member, energy-storing means, means whereby movement of said member in one direction stores energy in said energy-storing means, a magnet, an armature therefor, means, including a lost motion connection, whereby said longitudinally movable member may move said armature in either direction, movable contacts operatively associated with said armature, stationary contacts adapted to cooperate 25 with said movable contacts, means for preventing engagement of certain of said contacts, means actuated by said stored energy for rendering said preventive means ineffective, and means for retarding said actuating means.
- 30 8. In an electromagnetic switching mechanism a longitudinally movable member, energy-storing means, means whereby movement of said member in one direction stores energy in said energy-storing means, a magnet, an armature therefor, means, including a lost motion connection, whereby said longitudinally movable member may move said armature in either direction, movable contacts operatively associated with said armature, stationary contacts adapted to cooperate 35 with said movable contacts, means for preventing engagement of certain of said contacts, means actuated by said stored energy for rendering said preventive means ineffective, and means operatively associated with said longitudinally movable member for controlling said certain contacts.
- 40 9. In an electromagnetic switching mechanism, a magnet, an armature therefor, a floating lever pivoted to said armature, a movable contact actuated by one end of said lever, a stationary contact co-operable with said movable contact, a second movable contact actuated by the other end of said lever, a second stationary contact co-operable with 45 said second movable contact, a latch for holding said other end of said lever in a position to prevent engagement of said second contacts, whereby when said armature is moved 50 towards said magnet, said first contacts will come into engagement and if said latch is released said second contacts will come into engagement.
10. In an electromagnetic switching mechanism, a magnet, an armature therefor, a floating lever pivoted to said armature, stationary contacts disposed on one side of said lever on each side of the pivot, a movable contact associated with each portion of said lever, and means whereby said lever is caused to oscillate so as to first cause engagement of the stationary and movable contacts at one end, then engagement of the contacts at the other end, and then disengagement of the contacts at the first end while said contacts at said other end remain in engagement. 55
11. In an automatic controller of the type having a first-position control coil and a second-position control coil, a switch for controlling said first-position coil, a coil connectible in shunt to said control switch, a switch in said shunt circuit, a switch for transferring energization from said first-position to said second-position coil, and a single armature actuatable by said shunt coil for controlling both said shunt switch and said transfer switch. 60
12. In an electromagnetic switch mechanism, a magnet, an armature therefor, a floating lever pivoted to said armature, stationary contacts disposed at one side of said lever on each side of the pivot, a movable contact associated with each portion of said lever, and means whereby said lever may be caused to oscillate so as to first cause engagement of the stationary and movable contacts at one end, then engagement of the contacts at the other end and then at will as desired, disengagement of the contacts at the first end while said contacts at said other end remain in engagement. 65
13. In an electromagnetic controller of the type having a first-position control coil and a second-position control coil, a switch for controlling said first-position coil, a coil connectible in shunt to said control switch, a switch in said shunt circuit, a switch for transferring energization from said first-position to said second-position coil and means for at will causing said shunt switch to open or not to open when energization is transferred to said second position coil. 70
14. In combination with a motor controller of the type having connecting means whereby a motor may be connected in starting relation to a source of supply and then in running relation to said supply and having electromagnetically actuated means for controlling said connecting means, of self-contained means comprising operatively assembled elements including electromagnetic devices mounted on a common support for causing said electromagnetically actuated means to automatically connect said motor 75

in starting relation for a predetermined time and then to connect it in running relation, said self-contained means being bodily removable without disturbing said connecting means.

15. In combination with a motor controller of the type having a first position control coil and a second position control coil, a control switch for initiating energization of said first position control coil, and connecting means controlled by said first position coil whereby a motor may be connected in starting relation to a source of supply and connecting means controlled by said second

position coil whereby said motor may be 15 connected in running relation to said supply, of self-contained means comprising operatively assembled elements including all necessary contactors mounted on a common support for automatically causing said first position coil to connect said motor in starting relation and with a delay to connect it in running relation, said self-contained means being bodily removable without disturbing either of said connecting means.

In testimony whereof, the signature of the inventor is affixed hereto.

HERBERT W. CHENEY.
